BONE PLATE

Kenneth Townsend and Charles W. Gilfillan,
Hollywood, Calif.

Application April 13, 1942, Serial No. 438,838

2 Claims. (Cl. 128-92)

1.

Our invention relates to the art of bone setting, and has among its objects and advantages the provision of an improved bone plate.

In the accompanying drawing:

Figure 1 is a view of a fractured femur illustrating our invention applied thereto;

Figure 2 is a face view of the bone plate structure applied to the femur of Figure 1;

Figure 3 is a sectional view taken along the line 3-3 of Figure 1; and

Figure 4 is a perspective view of portions of two overlapping bone plates.

In the embodiment selected for illustration, the drawing illustrates two overlapping bone plates 10 secured to the fractured femur 12 by means of screws 14. The plates 10 are identical. Our bone plate is made of austenitic (hardened by cold working) stainless steel. The non-corrosive alloy preferably contains eight per cent of nickel and eighteen per cent of chromium. The bone plate is 20 cm. in length, 1.4 cm. in width and 0.4 cm. in thickness. A series of slots 16 for the screws 14 is provided along the longitudinal medial line of the plate, which slots are 1 cm. in length with widths slightly larger than the 6-32 or 6-20 machine screw. The slots are spaced 1 cm. apart.

The two marginal side edges of the plate are deformed to provide V-shaped contours 18 wherein the outside flanges 20 are considerably wider than the inside flanges 22 so as to bring the flanges 20 into bone engagement with the body of the plate spaced from the bone.

In operation, the plate may be cut at the operating table to the desired length. If necessary, the plate may then be molded or contoured to the bone contour through the aid of pliers. While an assistant approximates the fragments with bone-holding forceps, the plate is applied to the exposed bone, and holes (#36 drill) are drilled in the middle of the slots 16, through both cortices, and the screws inserted. The screws 14 are of the fluted type, which renders the screws self-tapping.

The longitudinal slots 16 are characterized by many advantages over the conventional round or countersunk screw holes. The fracture need not be in apposition when the plate is applied. The ends of the fracture may be more than one-quarter inch apart. The screws are sunk to light contact with the plate, pressure is then applied above and below on the fractured member, the fracture thereby being accurately reduced. The screws are then tightened. After muscle tone has been restored postoperatively, the pull only

tends to further reduce the fractured surfaces, promoting quicker healing. Plaster casts are unnecessary, light suspension or traction being used for a short period, or walking calipers.

5 The plate is corrugated longitudinally to the contour of a modified M in cross section, which allows maximum strength in a plate of relatively thin gauge metal. The corrugated cross section is of such contour as to allow only the two outer 10 flanges to come in contact with the bone, thus having relatively small bone contact, which allows new bone to form under the body of the plate. The corrugated contour of the plate, when applied to the convex surface of the bone, tends to 15 maintain the original longitudinal axis of the fractured bone fragments. The plate action prevents lateral stresses on the shafts of the screws used to hold the plate, which helps to prevent loosening of the screws. Figures 1 and 2 illustrate two stacked plates, such stacking being desirable in connection with femurs, large humeri and tibiae. For double fractures of the femur, tibia or humerus, i. e., where fractures involve the upper third and lower third of the bone, 20 thereby producing a free fragment, the plates may be overlapped and staggered endwise to maintain a continuous metal truss. In connection with conventional plates, this type of fracture necessitates two plates without continuous 25 metal bridging. The corrugated contour allows the plates to be stacked or nested for additional strength as needed. Such stacking of the plates provides a leaf spring action, which counteracts sudden stresses in the fractured member, caused 30 by sudden muscle contracture or spasm, falling of the patient, or undue early weight bearing of the patient. Because of the overlapping coaction of nested plates, one or more free fragments of bone may be completely bridged with a metal 35 truss. The thin gauge of the plate allows it to be cut at the time of the operation, when the exact length has been decided upon. Thus many 40 plates of different lengths are not required as is necessary with the conventional bone plates. 45 The plate is easily bent to the longitudinal contour of the bone, even to right angles, without danger of breaking the plate. This is done at the time of the operation with the field exposed.

The slots through which the screws 14 pass allow the muscle pull to more closely approximate the fracture surfaces. In connection with conventional plates, the cortex on the plate side is often held apart while the opposite cortex is closely approximated, thus permitting undue 55 strain on the plate. Whether the plates are used

singly or in nested relationship, the cross sectional end contour and the slotted feature function in the same manner. The combined strength of the two plates is greater than two individual plates because of the leaf spring action. The fluted end of the screw 14 has an eccentric point formation and the fluted formation extends a considerable distance longitudinally of the screw. Such a screw allows a smaller hole to be used in the bone with greater holding power, and with about forty per cent greater tapping ease.

Without further elaboration, the foregoing will so fully illustrate our invention, that others may, by applying current knowledge, readily adapt the same for use under various conditions of service.

10

15

We claim:

1. A combination brace for fractured bones comprising a plurality of comparatively thin elongated plates in laminated relation providing a leaf spring-like brace, each of said plates having the same shape in cross section providing nesting thereof, and each of said plates having a centrally disposed flat web with inverted V-shape flanges at the edges and with the outer legs of said V-shape flanges longer than the inner legs providing means spacing the centrally disposed web from a plane across the outer edges of the outer legs of the flanges, said centrally disposed webs having spaced elongated centrally positioned screw receiving slots therein adapted to register with the plates nested with the ends aligned and also with the plates staggered.

2. A connecting plate for fractured bones comprising an elongated strip of material having

spaced slots therein extending continuously throughout the length thereof, and in which the said strip, in cross section, comprises a flat intermediate area in which the slots are positioned, with the sides of the strip at the edges of the flat area extending upwardly and then downwardly assuming V-shapes with the extreme edges positioned below the plane of the said flat area thereby spacing the flat area from a plane corresponding with the said extreme edges providing a springy gripping action of the said plate with a bone on which it may be secured by screws through the said slots.
